UNITED STATES PATENT OFFICE

MAXWELL M. UPSON, OF ENGLEWOOD, NEW JERSEY, ASSIGNOR TO RAYMOND CONCRETE
PILE COMPANY, OF NEW YORK, N. Y., A CORPORATION OF NEW JERSEY

REVETMENT MAT

Application filed September 26, 1929. Serial No. 395,211.

This invention pertains to revetment mats of the kind now being used in the control of the Mississippi River.

Such revetments are composed of small 5 concrete slabs tied together by wires or cables to form large articulated concrete mats with which the river bank is paved to a point well out in the stream.

One objection to this type of revetment is 10 the fact that during periods of low water, when the mat is exposed to air and dampness, the wires or cables rust away between the slabs and the slabs are thus liable to be pushed out of position by contact of barges, 15 logs or other floating material.

The principal object of the present invention is to so protect the wires between slabs that they will never be exposed to the elements and will therefore not rust away. 20 This is accomplished by enclosing the cables between slabs with elastic material which maintains intimate contact with the concrete of the slabs so as to exclude air or dampness from the cables. The material is also flexible 25 so as to permit free articulation of the mat structure. Preferably, the sealing material is a tar or asphalt preparation poured into molds of paper, as will be described in detail.

30 Further and other objects and advantages will be apparent from the specification and claims, and from the drawings which show by way of illustration what is considered the preferred form of the invention.

35 Fig. 1 shows the method of discharging the articulated mat from a barge onto the river bank.

Fig. 2 is an enlarged cross-section showing 40 details of the molds in which the slabs are cast, with paper mold in position to receive the sealing material.

Fig. 3 is the same as Fig. 2 after the sealing material has been poured into the paper mold.

45 Fig. 4 is the same as Fig. 3 after the slab molds have been filled with concrete.

Fig. 5 is a cross-section on line 5—5 of Fig. 2.

50 Fig. 6 is a cross-section on line 6—6 of Fig. 4.

Fig. 7 shows a modified form of the invention.

Fig. 8 is a cross-section on line 8—8 of Fig. 7.

Fig. 9 is a perspective view of several interconnected slabs of the mat to which the present invention has been applied. 55

To form the articulated mat, slab molds are interconnected in rows lengthwise and crosswise. Cables or wires are stretched 60 lengthwise and crosswise through the empty molds and become embedded in the concrete when it is subsequently poured into the molds. Heretofore the cables between the molds were uncovered and unprotected. According to the present invention, these unexposed portions of cable are covered before 65 the concrete is poured, the cable covering being of such nature as to form close contact with the concrete of the slabs when they are 70 poured.

After the slabs are set, the mat is discharged onto the river bank over the end or side of a barge. This operation is shown in Fig. 1, in which slabs 20 have been cast in 75 molds 22. Cables 24 and 26 pass through the slabs and tie them together in articulated relationship in both directions. These cables, between slabs 20, are enclosed in protecting casings 30. 80

After the molds pass over the curved discharge track 32 the slabs are deposited on the river bed 34 and the empty molds pass back to the left to be refilled.

As shown in Figs. 2 to 8, molds 22 are provided with overlapping trough-like projections 36 and 38. For the purposes of this invention I place in these troughs a paper mold which may take the form of two end walls 90 40 having inwardly extending flanges 42. These walls and their flanges are of such shape that they fit snugly into troughs 36 and 38 and are of such stiffness that they hold 95 themselves in position by frictional contact while the sealing material is being poured into them. In order that they may readily be placed in position their lower portions are split as indicated by line 44 (Fig. 5). Walls 40 do not fit the cable closely but are cut away 100

to provide clearance 46 around the cable for a purpose which will appear.

Although molds 40 have been mentioned as being made of paper, they may be of any material having suitable characteristics.

With molds 40 in position as in Fig. 2, melted tar, asphalt, or other suitable material is poured into the mold to form when set a flexible elastic casing 30 about the portion of the cable within the mold. Some of the molten material flows into and through the ring-like space 46 to form a protruding collar 48 about the cable and extending slightly into the spaces to be filled with concrete in molds 22. After casings 30 have set, the walls 40 may be torn off or cut away in order to provide large contact surfaces between casing 30 and concrete slab 20, but, if desired, the walls may be left in position, as in Fig. 4, when concrete is poured in molds 22 to form slabs 20. If molds 40 are left intact, collars 48 serve to make intimate contact with the concrete so as to exclude the surrounding element from the cable in case the mold material should disintegrate. The above described arrangement, shown in finished form in Figs. 4 and 9, is effective to protect the cable throughout its length, the concrete protecting the portions contained within the slabs and the elastic casing 30 protecting the portions between the slabs even when flexing thereof occurs.

Figs. 7 and 8 show an optional arrangement in which casing 30 is replaced by a sleeve 50 placed around the cable in position to have its ends embedded in slabs 20 when they are poured (Fig. 7). Sleeve 50 is of suitable flexible, elastic, adhesive material such as tar or asphalt. For convenience of application it may be in sheet form, wrapped around the cable as indicated in Fig. 8.

If the surface of the material of the sleeve is not sufficiently adhesive to insure a tight joint where overlapped, the sleeve may be coated with an adhesive before wrapping, or clamps may be applied to the sleeve if desired.

It is to be understood that the invention is not limited to the specific embodiment herein described and illustrated but may be used in other ways without departure from its spirit as defined in the appended claims.

I claim—

1. An articulated mat for revetments comprising in combination, a plurality of spaced concrete slabs, flexible members interconnecting said slabs and holding the same in spaced relation to permit movement relative to each other, and casings enclosing said members, for the purpose set forth.

2. An articulated mat for revetments comprising in combination, a plurality of spaced concrete slabs, flexible members interconnecting said slabs and holding the same in spaced relation to permit movement relative

to each other, and elastic casings enclosing said members between said slabs in order to protect said members from the element surrounding them.

3. An articulated mat for revetments comprising in combination, a plurality of spaced concrete slabs, cables passing through said slabs and the spaces between them and holding said slabs in spaced relation, and means for protecting said cables in said spaces from contact with the surrounding element.

4. The invention set forth in claim 3 in which said protecting means comprises a tar-like sleeve surrounding said cable and in contact with the adjacent slabs.

5. The invention set forth in claim 3 in which said protecting means comprises a sheet of weather-proof material wrapped around said cable and having its ends embedded in the adjacent slabs.

6. In an articulated mat for revetments comprising a plurality of spaced concrete slabs, flexible members interconnecting said slabs to hold the same in spaced relation and permit relative movement therebetween, and elastic casings enclosing said members between said slabs and projecting into said slabs.

7. An articulated mat for revetments comprising, in combination, a plurality of spaced concrete slabs, flexible members passing through said slabs to reinforce the same, said flexible members interconnecting said slabs to hold the same in spaced relation and permit relative movement therebetween and elastic casings partially embedded in the slabs and enclosing said members between the slabs to protect said members from the surrounding elements.

In testimony whereof I hereto affix my signature.

MAXWELL M. UPSON.
